UNITED STATES PATENT OFFICE.

BEN ORLANDO DARROW, OF KERN, CALIFORNIA, ASSIGNOR TO GEORGE W. MAXWELL,
OF SAN FRANCISCO, CALIFORNIA.

CONTAINER.

964,621.

Specification of Letters Patent. Patented July 19, 1910.

Application filed June 28, 1909. Serial No. 504,896.

To all whom it may concern:

Be it known that I, BEN O. DARROW, a citizen of the United States of America, residing at Kern city, in the county of Kern and State of California, have invented a new and useful Improvement in Containers, of which the following is a specification.

This invention relates to containers preferably made from fibrous material, as paper, and has for one of its objects to render the same waterproof in any desired manner, preferably by providing the interior with one or more coatings of waterproof material.

Another object is to form the body of the container from two thicknesses of material, said material preferably constituting a single length or piece having the portions thereof forming the different layers of different widths so as to form a shoulder upon the interior at each end.

Another object is to provide means at one or both ends for temporarily securing an end piece therein, as by forming tongues upon said end piece and the sides of the container and interlocking them, as by rolling them inward upon each other.

Other objects of the invention will become apparent as the invention is herein-after more fully disclosed, reference being had to the accompanying drawings which form a part of the specification and in which—

Figure 1 is a longitudinal, central, sectional view of one form of container embodying my invention. Fig. 2 is an end view, partly in section, looking down, the section being taken substantially midway of the length of the package. Fig. 3 is a diametrical, sectional view of the cover before the same is inserted. Fig. 4 is a plan view of the bottom. Fig. 5 is a plan view of the blank from which the sides of the container are formed. Fig. 6 is an end view of a cylindrical container.

Referring more particularly to the drawings which are for illustrative purposes only, and, therefore, are not drawn to any particular scale, 1 indicates the sides or main portion of the container within which end pieces are placed, the bottom 2 being preferably permanently secured therein and the top or cover 3 being adapted to be inserted after the container has been filled.

The sides 1 are preferably formed from a piece or strip 4 of fibrous material, such as manila or other suitable paper.

As will be seen by an examination of Fig. 5 the ends 5 and 6 of the blank are of different widths with shoulders 7 formed therebetween substantially midway the length of the blank. The narrower end or portion of the blank is adapted to form the inner layer of the wall of the container and therefore its length is substantially equal to the internal diameter of the container whether the same be rectangular, as shown in Fig. 2, or circular, as shown in Fig. 6. The wider end of the blank is also longer than the narrower end, so that after the narrower end 7 has been rolled or formed into the proper shape for the internal layer of the container the outer layer is then wrapped around the inner layer with its edges projecting beyond the edges of the narrower end and its free end extending beyond the lap or the free end of the inner layer far enough to permit of its forming a very strong joint, as shown at 8 in Fig. 2. Before the wider end is thus wrapped around the inner end water-proof material is preferably placed between said layers, preferably as a coating 9 which is applied upon the inner face of said wider portion.

By forming the body of the container in this manner it will be seen that a shoulder 10 is formed entirely around the interior of each end of the container of a width equal to the thickness of the paper employed against which the top and bottom 3 and 2, respectively, are adapted to engage when the container is completed and closed. A wall or flange 11 is also formed of a width equal to the excess of the width of the wider end of the blank over the width of the narrower end, the edges of the narrower end of the blank forming the shoulders as above described. Where the bottom 2 is permanently secured in the container, as shown in Fig. 1, it is preferably made a trifle larger than the internal diameter of the flange 11 at that end so that when it is forced in against its shoulder a bead 12 will be formed around the outside of the container, thereby assisting materially by friction in preventing the removal of the bottom. To further assist in holding the bottom in position the outer edge of the flange

may be rolled or curled in against the bottom of the bottom piece, as shown at 13 in Fig. 2.

Where the top or cover 3 of the container 5 is not inserted in the same manner as the bottom 2, as above described, it can be temporarily secured in position, as with the construction shown in Fig. 1, the upper end wall or flange being preferably slightly 10 flared outward, as shown at 14, from the shoulder 10. With this form of construction the cover 3 is also preferably provided with a flaring wall or flange 15 which is adapted to be forced down into the flared 15 portion 14 until the cover rests firmly against said shoulder 10 which will cause the outer edges of said flanges to be substantially even with each other, the wall or flange of the cover being preferably of a 20 less height than the wall of the container, as shown at 16. In order to further assist in holding the cover against accidental removal the walls 14 and 15 are preferably slitted longitudinally at a slight distance 25 apart, as shown at 17, and the tongues 18 and 19 formed thereby are crimped or rolled together into a double roll, as shown at 20, which extends in so as to overhang the cover 3 and, if desired, to bear against the same.

30 After the body has been formed as above described and the bottom inserted therein the interior of the container, as also the inner face of the cover, is preferably coated with a coating of suitable material, as 35 paraffin, which will assist in preventing any leakage that might occur and will also render the interior of the container water-proof and also adapted to preserve its contents without being contaminated by the material 40 from which said container is formed. In addition to this, by making the coating from paraffin the water-proof coating which is applied between the layers of the container will be prevented from coming in contact 45 with the contents of the container, especially at the inner edge of the inner layer, and, therefore, may be of a substance such as ordinary glue, which under other circumstances, or without the internal coating, 50 could not be used owing to its contamination of the contents of the container. The use of the water-proof coating between the layers of the sides of the container will also prevent the passage of the material of the 55 inner coating through the paper walls to the exterior where it would give the same a mottled appearance or otherwise militate against its use. By preserving the outer

layer or surface of the container in its original condition in this manner it can be utilized for printing or applying labels or other desired matter thereto.

By making the container substantially rectangular, as shown more particularly in Fig. 2, the containers can be nested together 65 very closely without the loss that occurs with cylindrical forms and in addition to that the corners are preferably slightly rounded, as shown at 21, which permits of the correspondingly rounded corners 22 of 70 the bottom and top being forced into such close engagement with the corners of the container that leakage at that point is prevented, and especially with the flanged upper end and flanged cover 3. A further advantage secured by extending the wall or flange 14 at the upper end and rounding the same as above described is the formation of 75 a spout, as it were, by means of which the contents of the container may be more 80 readily emptied and especially when such contents are in a liquid form.

Although I contemplate using the form of container as above described for the reception and storage of milk, as when the 85 same is being delivered to the customers, it is evident that the same can be utilized for other purposes, as the storing of fruits, syrups, &c., either for a greater or shorter length of time. The container can be 90 cheaply formed from ordinary material and will possess great strength and durability and will have many points of advantage as above fully set forth.

Having described my invention, I claim: 95

A container comprising a blank having a narrow end, and a wide end, of greater length than the narrow end, and coiled, so as to form inner and outer layers; the ends of the blank being overlapped and the outer 100 layer providing a flaring end projecting beyond the inner layer and having cover retaining tongues and a cover formed with flaring walls and seated on the outer end of the inner layer and within the flaring outer 105 end of the outer layer and having tongues coinciding with the tongues of the flaring end.

In testimony whereof, I have hereunto set my hand at Kern city, California, this 8th 110 day of June 1909.

BEN ORLANDO DARROW.

In presence of—

E. C. O'BOYLE,
J. K. SMITH.
